[57] ABSTRACT

An excavated mine shaft being provided with inner and outer concrete liners extending the depth of any water-bearing strata through which the shaft extends, and a barrier positioned between said inner and outer concrete liners and being impervious to moisture and expansible upon being subjected to moisture, and the method of forming the same waterproof mine shaft.

7 Claims, 4 Drawing Figures

PATENTED JAN 25 1972

WATERPROOF SHAFT AND METHOD OF FORMING SAME

This invention relates broadly to the art of water-proofed mine shafts composed of inner and outer concrete liners with a moisture barrier therebetween, and to the method of forming same; and the nature and objects of the invention will be readily recognized and understood by those skilled in the arts to which it relates in the light of the following explanation and detailed description of the accompanying drawings illustrating what we at present believe to be preferred embodiments or mechanical expressions of our invention from among various other forms, arrangements, combinations and constructions, of which the invention is capable within the spirit and scope thereof.

In many instances excavated mine shafts penetrate some water-bearing strata between the earth's surface and the ultimate depth of the mine shaft. The mine shafts in which we are particularly interested are conventionally composed of cylindrical inner and outer concrete liners, and it has been our experience with shafts of this general character that where a shaft passes through the aforementioned water-bearing strata, moisture or water seeps through the shaft lining.

This seepage of water introduces many problems, and it is our prime purpose to prevent this seepage of water through the inner liner. As an example of the undesirable conditions which are created by this seepage of water, when such seepage occurs, it is necessary to use a costly system of pumps, or some other system of water removal, and during freezing weather ice often forms on the inside surface of the shaft liner which causes dangerous conditions for both men and equipment, as the ice is likely to fall causing injury and damage.

The mine shaft of this invention comprises generally inner and outer concrete liners which normally pass through a water-bearing strata, and where the shaft passes through such water-bearing strata we dispose, in position between these liners, a moistureproof barrier which is formed of any suitable material which is characterized by its capability to expand when subjected to moisture. It will be recognized that this expansive quality of the water-proofing barrier results in a sound seal between the inner and outer liners, and this expansive characteristic also insures a closure of any imperfections which may be present in the barrier so that the barrier has a "self-healing" effect when it is subjected to moisture. These imperfections in the barrier may be caused in any number of ways, for instance, in the installation of the barrier it may be damaged and of course in the manufacture thereof undesirable interstices may be present in the body of the material of the barrier. One, from among many, materials which may be used with advantage as the moistureproof barrier is bentonite which is a soft, porous material which has the characteristic of expanding upon contact with water up to 10 times its original volume, which not only produces the aforesaid "self-healing" effect but also, due to these expansive qualities, produces an excellent seal. A further significant advantage of the use of a material for the moistureproof barrier which is endowed with these expansive characteristics is that the panels or sheets of the material need not be sealed at their edges when they are wound into position between the two cylindrical liners, instead it is only necessary to overlap the adjacent edges, and it will be appreciated that upon the expansion thereof, resulting from contact with moisture or water, a good seal at the edges will be provided.

We have found that it is desirable to make up the sheets or panels of the waterproof barrier material in a sandwich manner, so that a paper backing is provided on at least one face of the material, and preferably on both. This arrangement substantially facilitates the installation of the barrier.

The waterproof mine shaft of this invention is commercially practical, is relatively inexpensive to produce and easy to install.

Our invention also contemplates a novel and ingenious method of constructing such water-proofed mine shafts, as will be pointed out in detail hereinafter.

With the foregoing general objects, features and results in view, as well as certain others which will be apparent from the following explanation, the invention consists in certain novel features in design, construction, mounting and combination of elements, as will be more fully and particularly referred to and specified hereinafter.

Referring to the accompanying drawings:

FIG. 1 is a vertical, sectional view illustrating a mine shaft which is water-proofed throughout the length thereof which runs through a water-bearing strata.

FIG. 2 is a top plan view of the water-proofed mine shaft.

FIG. 3 is a perspective view of the waterproof barrier with parts thereof broken away, and with a portion of the paper backing peeled from the waterproof barrier.

FIG. 4 is a view in perspective of the waterproof barrier, with parts thereof broken away, and with a section of the paper backing peeled from the barrier disclosing an imperfection in the waterproof barrier.

In the preparation of mine shafts in accordance with the present invention the shaft is excavated from the earth's surface 1 to the ultimate depth of the shaft. In most instances the excavation extends through a water-bearing strata 3 which extends from the earth's surface downwardly along the shaft to some point, such as the point 5, in the example illustrated in the drawings.

Consideration of FIG. 1 of the drawings clearly indicates that the excavated shaft 6 is of greater diameter throughout the length thereof which passes through the water-bearing strata than is that portion thereof which extends below the water-bearing strata. When the shaft has been excavated into the ground, as described above, a cylindrical concrete outer liner 7 is positioned within the shaft with its external circumferential surface in engagement with the walls of the excavation. The length of the outer liner 7 is substantially equal to the depth of the water-bearing strata 3. When this outer liner 7 is positioned, as described, against the wall of the excavation it provides support for this water-bearing strata and also provides a relatively smooth interior surface against which the moistureproof barrier is installed, as will be explained hereinafter. When the concreting of the outer liner is completed a moistureproof barrier indicated generally by the number 11 is installed on the inside circumferential surface of the outer liner 7. It will be evident that the moistureproof barrier 11 covers and abuts substantially the entire inner surface of the outer liner 7. The moistureproof barrier, indicated in its entirety by the numeral 11, consists of a body 13 of the desirable type of water-proofing agent and it is preferable, though not necessary, that the moistureproof barrier be provided with a paper backing 15' on at least one side thereof, and it may be provided on both sides thereof if found desirable. It has been our experience in this art that installation of the water-proofing barrier is facilitated by providing this sandwich type of article.

The moistureproof barrier is preferably furnished in sheets or panels and in the installation thereof is wound to conform generally to the interior configuration of the outer liner 7.

Upon installation of the moistureproof barrier 13 as described above an inner cylinder concrete liner 9 of less diameter than the diameter of the outer liner 7 is inserted into the shaft with its exterior circumferential surface in engagement with the moistureproof barrier. The inner liner 9 functions as the final surface and as a containment and protection for the moistureproof barrier 13. It will be noticed that the inner liner 9 extends not only through the water-bearing strata 3 but also downwardly and therebeyond.

The thickness of the moistureproof barrier depends upon the known or reasonably expected moisture conditions in the water-bearing strata.

It is significant to recognize that we have chosen to use a moistureproof barrier 11 which is characterized by its ability to expand in all directions when it is subjected to the action of moisture. Such characteristics of the moistureproof barrier are highly advantageous for a substantial number of reasons.

When the sheets of the moistureproof barrier have been installed in position between the outer and inner concrete liners 7 and 9, respectively, where such liners extend through the water-bearing strata, it will be understood that if, and when moisture penetrates the outer liner 7 and comes into contact with the moistureproof barrier 11 such barrier will expand and will thereby provide a sound seal between the two liners preventing moisture from reaching the inner liner 9 and passing therethrough to cause the difficulties and problems discussed hereinabove.

In using a moistureproof barrier having these expandable characteristics it is not necessary to seal the adjacent edges of the sheets or panels of the material, instead the panels at their edges are overlapped as illustrated at 15 in FIG. 2 of the drawings, and due to the expansive qualities of the material, when in contact with moisture or water, a good and sound seal will be formed between the sheets, or panels, of the barrier material. It will be obvious that this elimination of the necessity for sealing the adjacent edges of the sheets, or panels, saves substantial time in the installation of the moistureproof barrier without sacrificing the resulting excellent seal between the sheets, or panels of the barrier.

In order for the barrier to properly function as a moisture-proofing means it will be evident that the body 13 of the barrier must be continuous and not have interstices or punctures therein through which moisture or water could pass. We have found that it often happens that the body of the barrier is not continuous and may have openings or imperfections such as 17 therein, as illustrated in FIG. 4. The material from which we make the moistureproof barrier, due to its expansive qualities upon contact with moisture or water, has a self-healing effect which operates to close such openings or interstices 17 to provide a continuous moisture-proofing body. These imperfections in the barrier which would reduce or substantially eliminate the water-proofing function may be caused by a variety of reasons such as by imperfect installation or by some damage that may later be caused.

We have discovered that bentonite is a particularly suitable material for use as the moisture-proofing agent. Bentonite is a soft, porous, moisture-absorbing rock composed mostly of clayey material and is endowed with the ability to expand upon contact with water or moisture up to 10 times its original volume which gives this moisture-proofing material an inherent self-healing and sealing effect.

While we have indicated that bentonite functions in a highly desirable manner when it is used as the moisture-proofing agent, we do not wish to limit this invention to the use of bentonite for other materials having expansive characteristics which produce the wanted results may be used in place of bentonite.

It is of some significance to appreciate that the inner concrete liner 9 should be of such thickness that no concrete inserts, formed holes or reinforcing steel will penetrate through it into the moisture barrier 11.

In the construction of the mine shaft, as disclosed herein, the earth is excavated whereupon the outer concrete liner 7 which is of a length sufficient to extend through the water-bearing strata is placed in the excavation, whereupon the

moisture barrier 11 is positioned in place against the interior circumferential surface of the outer liner and when this is completed the inner concrete liner 9 is placed in the excavation.

5 We claim:

1. A mine shaft passing through a water-bearing strata in the earth, including an inner liner passing through and extending downwardly into the earth beyond said water-bearing strata, an outer liner spaced from said inner liner and extending solely through said water-bearing strata, and a moistureproof barrier disposed between said inner and outer liners and extending solely through said water-bearing strata to prevent seepage of moisture through said inner liner and into said shaft, the exterior surface of said outer liner being in contact with the earth throughout its length and the exterior surface of said inner liner being in contact with the earth solely in that portion thereof which extends downwardly into the earth beyond said water-bearing strata.
2. A mine shaft in accordance with claim 1, wherein said moistureproof barrier is composed of sheets of moistureproof material, which expands upon contact with moisture.
3. A mine shaft in accordance with claim 2, wherein adjacent edges of said sheets of moistureproof material are overlapped.
4. A mine shaft in accordance with claim 3, wherein said moistureproof barrier is formed of bentonite.
5. A mine shaft in accordance with claim 5, wherein said moisture proof barrier is provided with a flexible backing sheet on at least one side thereof.
6. The method of constructing a waterproof mine shaft, which passes through a water-bearing strata in the earth comprising those steps of excavating the earth to provide a shaft extending into the earth below and beyond said water-bearing strata or greater diameter than the diameter of said shaft which extends into the earth below and beyond said water-bearing strata, inserting an outer liner of an external diameter substantially the same as the diameter of the excavated shaft where it passes through said water-bearing strata inserting a moistureproof barrier into said shaft in engagement with said outer liner and then inserting into said shaft an inner liner of substantially the same external diameter as the diameter of said shaft where it passes into the earth below and beyond said water-bearing strata, inserting the inner liner into said shaft so that the external surface of the inner liner is in contact with the earth where said inner liner extends into the earth below and beyond said water-bearing strata, and said inner liner is so inserted into the shaft that its external surface is in abutment with said moistureproof barrier where said inner liner extends through the water-bearing strata of said shaft.
7. The method of constructing a waterproof mine shaft in accordance with claim 6, wherein the shaft passes through a water-bearing strata in the earth and the method consists of forming said outer liner of a length substantially the same as the depth of said water-bearing strata and forming said moistureproof barrier of substantially equal length to the length of said outer liner, and forming said inner liner of a length greater than the length of said outer liner.
